INVENTOR:

UNITED STATES PATENT OFFICE

JOHN H. HERTNER, OF LAKWOOD, OHIO, ASSIGNOR TO THE HERTNER ELECTRIC COMPANY, OF CLEVELAND, OHIO, A CORPORATION OF OHIO

INSULATOR

Application filed February 18, 1932. Serial No. 593,296.

This invention relates to an electrical insulator and particularly to electrical insulation having especial utility in connection with electrical machinery or devices wherein it is necessary to insulate against low voltages. An illustration of the necessity for the use of such an insulation was found in the field windings of generators and motors where bare copper ribbon is wound on edge 10 or on the flat for series or interpole coils and wherein the heat developed is relatively high, although it will be realized that there are numerous other instances wherein an insulator embodying the present invention 15 may be advantageously used.

An object of the invention is to provide an electrical insulation which is mechanically strong and safe, yet of such character as to occupy a minimum amount of space.

Another object is to provide an electrical insulation which is substantially unaffected by high temperatures.

A further object is to provide an electrical insulation which, while mechanically strong, 25 is extremely thin and therefore can be accommodated in a small amount of space.

A still further object is to provide an electrical insulation which may be used for the additional purpose of providing for heat radiation.

Another additional object is to provide an electrical insulation which may be readily and economically manufactured and easily applied.

Further and additional objects of the invention will appear hereinafter during the following detailed description of the invention.

The invention in its broad aspect contemplates an electrical insulation formed of metal having thereon a non-conducting coating.

In order to more fully describe the invention and the manner in which the insulation may be used, reference should be had to the accompanying drawing and the description based thereon that is to follow.

In the drawing Fig. 1 is a perspective view of an edge wound coil, wherein the turns of copper ribbon are insulated from

each other by strips of insulation formed in accordance with the present invention;

Fig. 2 is a transverse sectional view taken substantially on line 2—2 of Fig. 1 looking in the direction of the arrows;

Fig. 3 is a top plan view showing the manner in which the insulation strips are arranged with respect to each other, the pole piece or core of the coil being indicated in dotted lines;

Fig. 4 is a sectional view taken substantially on line 4—4 of Fig. 3 looking in the direction of the arrows;

Fig. 5 is a sectional view on an enlarged scale taken substantially on line 5—5 of Fig. 6 looking in the direction of the arrows.

Fig. 6 is a sectional view of a flat wound coil and is taken substantially on line 6—6 of Fig. 7, looking in the direction of the arrows; and

Fig. 7 is a sectional view of a flat wound coil and is taken substantially on line 7—7 of Fig. 6, looking in the direction of the arrows.

It is important that insulation, which is used in various forms of electrical machinery or devices, be mechanically strong to insure it against being broken, but at the same time such insulation must necessarily be thin in order to occupy a minimum amount of space. In attaining the provision of an insulation that possesses great mechanical strength, but which is not bulky or thick, I propose to employ an insulation

formed of thin metallic strips having thereon a thin non-conducting coating. The metallic strips preferably should be extremely thin, but it will be understood that the thickness of the strips may be governed

according to the various needs of the particular instance in which they are used, such as the space in which the insulation is to be arranged and the pressure to which it will be subjected in use, and also by the further consideration of the price of the material.

The non-conducting coating that is applied to the strips may take various forms, such as a thin coating of vitreous enamel, a coating of phosphate of iron, or any other good non-conducting coating. At the present time it

is believed that a non-conducting coating formed of phosphate of iron or other non-oxidizing coating is the preferable coating to be applied to the strips and for that reason 5 the coating will be so described herein, it being understood, however, that the invention contemplates the use of other forms of coatings and that if subsequent developments indicate a more preferable form of coating, 10 such form is to be considered within the contemplation of the present invention in its broad aspect.

In carrying out the invention by the use of a non-conducting coating formed of 15 phosphate of iron, metallic blanks or strips, preferably extremely thin steel strips, are cut into the proper shape and are then immersed in or subjected to the action of a bath composed of a dilute solution of phosphoric acid, having in some instances, a suitable catalyst therein, such as ferrous phosphate, iron filings or the like, although it is not necessary in every instance to employ the catalyst. The phosphate of iron 20 coating might also be applied by passing an electric current through an electrolytic bath formed of a dilute solution of phosphoric acid and having the phosphate of iron coating electro-chemically deposited upon the 25 metallic blanks or strips. The thickness of the non-conducting phosphate of iron coating can be varied in accordance with the conditions to which the insulation will be subjected in use. The present invention 30 does not include broadly the coating of metal with a phosphate of iron coating for general use, since this is well known in the art, but it does include the provision of an electrical insulation in the form of metallic 35 blanks or strips having thereon a non-conducting coating such as a phosphate of iron coating.

In the accompanying drawing there is 40 illustrated in Figs. 1 to 5, inclusive, a coil having a pole piece or core 10 upon which a continuous ribbon of bare copper 11 is wound on edge, insulating pieces of fabric 12 being interposed between the core 10 and the inner edges of the copper ribbon 11 and the outer edges of the copper ribbon 11 and 45 bent laterally over the outermost turn of the copper ribbon, as indicated at 12a and under the innermost turn of the ribbon, as indicated at 12b. There is also provided, between the outermost turn of the ribbon and the laterally bent portion 12a of the fabric 12, an oval piece of fabric 13 while annular strips 14 of fiber or other suitable material extend between the portions 12b of the fabric 12 and foot portions 15 of the 50 core 10 and upwardly along the outer side of the coil, such annular strips 14 extending longitudinally of the coil for only a portion of its length. Since the construction of the coil per se forms no part of the present invention, and is well known in the art, a more 55

detailed description of such construction is unnecessary herein and it should suffice to say that the coil illustrated in Figs. 1 to 5, inclusive, of the drawing may be of any well known construction wherein a continuous 70 copper ribbon is wound on edge about a core or pole piece.

In adapting the insulation of the present invention for use with a coil, such as shown in Figs. 1 to 5, inclusive, it is proposed to 75 cut thin metallic strips 16 in the form of half ovals, of such size that when the strips are assembled in the coil each end of each half may overlap the adjacent end of the other half, as clearly indicated in Figs. 3 80 and 4. The semi-oval strips after being cut are then provided with the non-conducting coating, such coating being indicated at 17 in Figs. 3 and 5 and preferably being a phosphate of iron coating. As previously 85 mentioned, the thickness of the metallic strips, which are preferably steel strips, may vary to suit the different conditions of use while correspondingly the thickness of the non-conducting coating may also vary. 90 The strips with the non-conducting coating thereon are inserted edgewise between the turns of the copper ribbon coil 11, as clearly indicated in Figs. 1 and 2, the ends of each strip overlapping the ends of its co-operating strip, such cooperating strips forming together an oval of substantially the same size or configuration as the turns of the coil. The width of the strips may be 95 such that their outer edges will project a short distance outwardly of the outer edge of the copper ribbon 11, so that said strips will serve the additional purpose of radiating fins that will carry off the heat occasioned by the energy loss in the coil. 100

In Figs. 6 and 7 there is illustrated a coil 105 of the flat wound type and in which is employed insulation according to the present invention. Referring to Figs. 6 and 7 the core of the coil is indicated at 18 while the bare copper ribbon flat wound thereon is indicated at 19. The insulation is indicated at 20 and is a thin ribbon formed of thin metal, such as steel, and having thereon the non-conducting coating such as the metallic phosphate coating previously referred to and applied in the same manner. In constructing the coil the copper ribbon 19 and the insulating strip 20 are wound simultaneously upon the core 18, so that between each turn of the copper ribbon 19 there is a turn of the insulation 20. The width of the insulating strip 20 may be slightly greater than the width of the copper ribbon so that the edges of the insulating strip lie outwardly of the edges of the copper ribbon in order to carry off the heat produced in the coil, as in the construction illustrated in Figs. 1 to 5, inclusive.

It will be seen that the coated strips pro-

vide an insulation which, because it is composed mainly of metal such as steel, will have great mechanical strength and will not be likely to be accidentally broken. It will further be noted that since the strips and the non-conducting coating thereon are relatively thin that the insulation does not occupy much space, but at the same time possesses great mechanical strength. The insulation although being formed mainly of metal is substantially unaffected by the high temperatures produced by the energy loss and, since the insulation is of metal, it may be readily and economically manufactured by stamping or other processes and is easily applied by inserting the same edgewise between the turns of the coil or by winding the same upon the core in between the turns of the coil as in the flat wound type shown in Figs. 6 and 7.

Although several preferred embodiments of the uses to which the invention may be applied have been illustrated and described herein, it should be understood that the invention is susceptible of various other uses, modifications and adaptations within the scope of the appended claims.

Having thus described my invention, I claim:

- 30 1. An electrical insulator comprising a metallic strip having thereon a metallic phosphate coating.
- 25 2. An electrical insulator comprising a steel strip having thereon a phosphate of iron coating.

40 3. In combination, an electrical coil comprising a core, a conducting material wound on said core, and insulators formed of metal having a non-conducting coating arranged between the adjacent turns of said material.

45 4. In combination, an electrical coil comprising a core, a flat ribbon of conducting material wound thereon, and flat insulators formed of metal having a non-conducting coating arranged between the adjacent turns of said material.

50 5. In combination, an electrical coil comprising a core, a flat ribbon of conducting material wound thereon on edge, and flat insulators formed of metallic strips having a non-conducting coating arranged between the adjacent turns of said material.

55 6. In combination, an electrical coil comprising a core, a flat ribbon of conducting material wound edgewise thereon, and flat insulators formed of metal strips having a non-conducting coating thereon arranged between the adjacent turns of said material, said strips being of greater width than the width of said material and being inserted edgewise with respect to the core and having their outer edges lying laterally outwardly of the outer edge of said material.

60 7. In combination, an electrical coil comprising an elongated core, a flat ribbon of

conducting material wound thereon on edge, and insulators formed of flat metal strips having a non-conducting coating arranged between the adjacent turns of said material, said strips being arranged in cooperating pairs with the adjacent ends of the strips of each pair overlapping.

70 8. In combination, an electrical coil comprising a core, a flat copper ribbon wound thereon, and insulation arranged between the adjacent turns of said ribbon, said insulation being formed of thin strip metal having a chemically deposited phosphate of iron coating thereon.

75 9. In combination, an electrical coil comprising a core, a flat ribbon of conducting material wound thereon with its flat side encircling said core, and a metallic strip having a non-conducting coating thereon arranged between the adjacent turns of said material and insulating the same from each other.

80 10. In combination, an electrical coil comprising a core, a flat ribbon of conducting material wound thereon with its flat side encircling said core, and a metallic strip having a non-conducting coating thereon arranged between the adjacent turns of said material, said strip being of greater width than the width of said material and having its edges lying laterally outwardly of the outer edges of said material.

85 In testimony whereof, I hereunto affix my signature.
